ELECTRIC TERMINAL

Jesse J. Jorgensen, Ancon, C. Z.

Application December 1, 1944, Serial No. 566,176

1. Claim. (Cl. 173—363)

This invention relates to terminal assemblies, and more particularly, is directed to terminal assemblies for receiving conductor prongs for lighting circuits, electrical appliances, instruments, and the like, in which the making of a positive mechanical and electrical connection of a semi-permanent character is a prime consideration.

A main object of this invention is to provide a connector for a positive connection which is not subject to arcing, has a low contact resistance and is extremely simple to apply or remove.

Further objects of this invention will appear from the following description and claim, and from the accompanying drawings, wherein:

Figure 1 is a longitudinal cross-section of one embodiment of a terminal assembly according to this invention;

Figure 2 is a sectional view taken on line 2—2 of Figure 1;

Figure 3 is a sectional view taken on line 3—3 of Figure 1;

Figure 4 is a partial longitudinal cross-section of a modified terminal assembly according to this invention.

Referring to Figures 1 to 3, a male contact member 1 is shown secured to an appliance 2. Male contact member 1 is provided with an integral flange 3 and a threaded end portion 4. End portion 4 extends into the appliance and may be permanently connected electrically thereto. A nut 5 is used to secure the threaded end portion 4 to provide tight conductive contacts to terminal 6, which may be the flat loop portion of a conventional connector lug. Ordinary metal washers are used between the flange 3 and the outside wall of the appliance 2, and between the nut 5 and the inside wall of the appliance.

The female portion of the contact assembly comprises a cylindrical sleeve member 7 having an internally tapered bore 8 extending a substantial length inside the sleeve and terminating in a cylindrical cup-shaped top cavity 9. A flared chuck member or collet 10 of generally conical shape is fitted inside the sleeve member 7. Chuck member 10 is provided with a central bore 11 to receive male member 1. Bore 11 extends almost to the top of chuck member 10. The top portion of chuck member 10 is provided with a tapped collar portion 12 which is threadededly engaged by a machine screw 13 extending through an opening provided therefor in the top of sleeve 7. The wire 15 is positioned between washer 14 under the head of screw 13 and the top surface of sleeve 7.

Chuck member 10 is provided with a number

5 of longitudinal slots 16 extending substantially the length of the flared portions thereof, forming chuck segments or jaws 17 and permitting the chuck segments or jaws to be squeezed together responsive to wedging action of tapered surface 8 as the chuck member is retracted into sleeve 7 by the tightening of screw 13. The squeezing together of the chuck segments 17 is effective to establish a positive conductive grip 10 on male member 1.

In the embodiment of Figure 1, a coil spring 18 is provided in the cup-shaped cavity 9, bearing on shoulder 19 of the chuck member 10. The function of the spring is to facilitate the release 15 of the connector assembly when the machine screw 13 is loosened. The pressure of the spring tends to urge the chuck member 10 out of wedging relation to the tapered bore surface 8. The disengagement of the male and female connector 20 elements can be further aided by removing machine screw 13 and inserting a substantially longer screw and by driving in the longer screw until it contacts the top of male member 1. Further driving of the longer screw will push male member 1 towards the lower and wider end of chuck member 10.

Sleeve member 7 is provided at the top portion thereof with parallel outer flat surfaces 20 for engagement with a wrench so that the sleeve may 30 be held against rotation during the tightening or loosening of the connector assembly.

In Figure 4 a somewhat modified embodiment of the invention is disclosed wherein the spring member is omitted and wherein the top wall of 35 the sleeve member 7' is formed by a washer 21. This provides a somewhat cheaper assembly and retains most of the important features of the embodiment of Figure 1.

While the foregoing description sets forth the 40 invention in specific terms, it is to be understood that numerous changes in the shape, size and materials may be resorted to without departing from the spirit of this invention. It is, therefore, intended that no limitations on the invention be imposed other than as set forth by the 45 scope of the appended claim.

What is claimed is:

In an electric terminal assembly, including a 50 contact prong; the improvement comprising a socket member adapted to receive said prong, said socket member comprising a sleeve, said sleeve being formed with an internal bore, an end wall closing one end of said bore, said bore being outwardly flared toward said other end, said last-named end of said bore being open, said end wall

being formed with an axially-disposed aperture therethrough, an electrical contact screw extended through said aperture, said screw having a head outwardly of said end wall and adapted to clamp an electric wire against said end wall, a 5 collet-like chuck element slidable in said bore, said element having an axial bore slidably receiving said prong, said element having gripping segments surrounding said last-named bore, said segments having tapered outer surfaces complementary to said flared bore, said member being formed with an inner end wall closing said bore therein, said last-named end wall being formed with a tapped aperture therethrough threadedly engaging said screw whereby rotation of said 15 screw in one direction is operative to draw said member inwardly of said sleeve and move said segments into clamping engagement with said prong, said screw, member and prong being formed of current-conducting material, said member having a reduced inner end providing a shoulder, an expansive coil spring concentrically disposed about said end, one end of said spring bearing against said shoulder, and the

other end of said spring bearing against said end wall of said sleeve whereby to load said sleeve and member for relative movement in a prong-releasing direction.
